(57) **CLAIM**

The ornamental design for a vaporizer device with cartridge, as shown and described.

DESCRIPTION

1.1 is a top, rear, and right side perspective view of a vaporizer device with cartridge showing a first embodiment of our design;

1.2 is a top view thereof;

1.3 is a left view thereof;

1.4 is a rear view thereof;

1.5 is right side view thereof;

1.6 is a front view thereof; and

1.7 is a bottom view thereof.

2.1 is a top, rear, and right side perspective view of a vaporizer device with cartridge showing a second embodiment of our design;

2.2 is a top view thereof;

2.3 is a left view thereof;

2.4 is a rear view thereof;

2.5 is right side view thereof;

2.6 is a front view thereof; and

2.7 is a bottom view thereof.

3.1 is a top, rear, and right side perspective view of a vaporizer device with cartridge showing a third embodiment of our design;

3.2 is a top view thereof;

3.3 is a left view thereof;

3.4 is a rear view thereof;

3.5 is right side view thereof;

3.6 is a front view thereof; and,

3.7 is a bottom view thereof.
